JEWELRY DISPLAY RACK

Allan Robinson, Boston, Mass.

Application January 19, 1955, Serial No. 34,055

Term of patent 14 years

(Cl. D80—9)

FIG. 1

I claim:

The ornamental design for a jewelry display rack, as shown.
